SIGNORS TO RESERVE HOLDING COMPANY, OF CHICAGO, ILLINOIS, A CORPORATION
OF DELAWARE

TELEPHONE SYSTEM

Application filed July 5, 1929. Serial No. 376,215.

This invention relates to telephone systems in general but is concerned more particularly with small systems of the type commonly known as private branch exchanges and with the method of inter-connecting such systems with public telephone systems.

A private branch exchange, hereinafter designated P. B. X. is a relatively small but complete telephone system designed primarily for furnishing local telephone service between various telephones in a business establishment or other organization. Such exchanges are, in fact, branches of a public telephone system and are connected with the public system by one or more trunks as required by traffic conditions.

A private branch exchange may be of the manual or automatic type or it may be a combination of the two. In the latter type of exchange local calls are completed automatically by the branch exchange subscribers while all incoming calls from the public telephone system are intercepted and completed by an attendant. This arrangement is desirable since it is not usually practicable to list the local telephone number of each branch exchange subscriber in the public telephone directory.

A modified system has been proposed in which the P. B. X. switching apparatus is to be installed in an exchange of the public telephone system and separate lines extended to each P. B. X. telephone. This arrangement results in a considerable saving in auxiliary equipment such as storage batteries, ringing machines, etc. The system has not been entirely satisfactory, particularly when the P. B. X. is of the attended type as the additional line plant required offsets the saving in auxiliary equipment. The main object of this invention is the provision of an improved system of the above general type in which the objectional features inherent in previous systems are eliminated and which is adapted for commercial use.

In centralized switching systems of the type described there are often several business concerns between which there is considerable telephone traffic. Special trunking facilities between the two private exchanges

may be provided so that calls between these exchanges will not tie up equipment of the public exchange. The inter-exchange service may be full automatic or it may be handled on the same basis as incoming calls from the public exchange. It is with the latter type of service that this invention is concerned, one of the features being an arrangement whereby the same trunks are used for incoming calls from either the public exchange or from another private exchange. It will be understood that these trunks may also be made accessible to selectors of the public exchange if service conditions make such an arrangement desirable.

Other features of the invention relate to improved circuits and apparatus for providing more efficient and economical service in systems of the type described.

The foregoing features together with others not specifically mentioned will be explained in detail hereinafter, with reference to the drawings comprising Figs. 1, 2, 3, and 4. These drawings show by means of the usual circuit diagrams a sufficient amount of the equipment in a telephone system embodying the invention to permit the invention to be readily explained and understood. The drawings should be arranged vertically in numerical order with Fig. 1 at the top and with corresponding lines in alignment. The apparatus shown in Fig. 1 and Fig. 2 is assumed to be located in a public automatic exchange and that in Fig. 3 located on the premises of a P. B. X. subscriber. Fig. 4 is a schematic diagram showing the trunking between a main exchange and a branch exchange embodying the features of the invention.

Referring now to Fig. 1, CC is an incoming connector in which terminates two trunks, one accessible by way of the local and toll connectors of the public exchange, the other accessible by way of selectors in either the public exchange or another private exchange. A trunk from the connector also extends to the attendant's position, and by way of its bank wipers and banks, the connector has access to the various lines of the P. B. X. Mechanically, connector CC is

similar to the connector shown in United States Patent No. 1,580,490 to Jacobsen. The circuits of the switch which relate solely to its function as a connector, that is, the vertical and rotary stepping circuit, busy test, switching and ringing circuits are also similar to corresponding circuits of the above patent. Other circuits of the switch relating to functions other than those of a connector and to the directive control thereof form a part of this invention and will be described in detail later on. Associated with the connector are the usual ringing tone generator G, ringing interrupter I, and busy tone generator BT which are common to all switches, such as connector CC of the P. B. X. In practice, separate auxiliary equipment would not be provided for each P. B. X. but similar equipment of the public exchange would be used in common.

Referring to Fig. 2, LS and LS' represent lineswitches terminating respectively a P. B. X. line and a line from the attendant's position. These switches are of the well known rotary type having no normal or home position. Connector LC, shown in skeleton form, may be of the well known type commonly known as a P. A. X. connector such as that shown in U. S. Patent No. 1,582,226 to Ray. The connector is accessible to lineswitches of the P. B. X. and has access to these lines and to trunks both to the public exchange and to one or more other private exchanges. The connector switches over and functions as a selector when one of the outgoing trunk levels is called.

In Fig. 3 is shown two ordinary automatic substations T and T1 terminating in P. B. X. lines. Substation T is associated with lineswitch LS (Fig. 2) and substation T1 is associated with a similar lineswitch which is not shown. The attendant's telephone set AS includes the usual transmitter TR, receiver REC, calling device or dial CD, and is equipped with a key K for answering and extending calls over the extension line terminating in lineswitch LS1 (Fig. 2). Relay group TRG terminates the simplex trunk extending from connector CC, (Fig. 1), and is equipped with a key K1 for connecting the trunk with attendant's telephone set. Calling and supervisory lamps L1 and L2 associated with the trunk relays are located at the attendant's position.

Referring to Fig. 4, TM is a main exchange substation associated with a line terminating in lineswitch LSM which has access to local selectors such as selector SM. Incoming selector ISM terminates a trunk from a switching level of a branch exchange connector such as connector LC. The banks of incoming selectors and local selectors are multiplied. These selectors have access to the various main exchange connector groups including a group of rotary connectors of

which connector CM is one. The rotary connectors have access to the branch exchange line groups of which one trunk terminating in branch exchange connector CC is shown. Connectors CC and LC, lineswitches LS and LS1, operator's set AS, trunk relay group TRG and substations T and T1 are shown in detail in Figs. 1-3. It will be noted that a trunk from the banks of selector SM is shown extending to connector CC. This trunk may also be accessible to incoming selectors or switching connectors of other branch exchanges as will be explained in later paragraphs.

Connector CC and the associated trunk circuits are adapted to operate when called from either a connector or a selector. A call from an outside subscriber is extended to the connector which signals the attendant over the simplex control trunk. The attendant determines the name of the party wanted and then dials back over the trunk to set the wipers of the connector on the contacts to the proper P. B. X. line. The connector is then arranged to give the usual answering supervision to the calling subscriber as soon as the attendant answers. After extending the call the attendant disconnects the control trunk from the telephone set and the trunk relays operate to provide answering and disconnect supervision. In case the P. B. X. line called is busy, the attendant can release the connection and set up the call to another line while the calling subscriber waits. Both the connector and the attendant's set are arranged so that the dialling impulses cannot be heard.

The operation of the apparatus on toll calls is the same as on local calls except that the attendant is not signalled until the toll operator rings. The called line is signalled automatically, however, as in a local connection.

The attendant's position is also provided with a line over which local calls in the P. B. X. may be extended and received. The attendant as well as the P. B. X. subscribers can call public exchange subscribers and other inter-connected private exchanges by way of the local switching connectors and outgoing trunks. Local calls in the P. B. X. are completed under control of a calling subscriber and do not involve any of the public exchange apparatus.

Having briefly described the operation and the apparatus involved, a detailed description will now be given. A local call from a public exchange subscriber to a P. B. X. line, such as the line terminating in substation T1 will be considered first. The calling subscriber extends the call over the public exchange apparatus in the usual way, a local rotary connector such as connector CM (Fig. 4) connecting with a trunk to the P. B. X. for example, the trunk comprising conductors

2', 3' and 4' terminating in connector CC. Ground is extended over release trunk conductor 4' to relay 102 by way of contacts 196. Relay 102 operates, connects a bridge including condenser 181 and the upper winding of relay 101 across the incoming line conductors at contacts 125 and 126, connects a busy-ground to release trunk conductor 4 of the selector level trunk at contacts 123 and 10 closes a point in the simplex control circuit at contacts 129. This latter circuit is not effective at this time, however, since battery is connected to both ends of the simplex trunk. The connector in the public exchange 15 now sends out ringing current in the usual way and relay 101 responds, completes a locking circuit for its lower winding at contacts 121 and at contacts 119 closes a circuit for relay 103. Ringing impulses from the connector will have no further effect on connector CC due to the opening of the bridge at contacts 120. Relay 103 operates, closes 20 a circuit for relay 104 at contacts 130 and connects ground to the simplex trunk at contacts 133. Relay 104 operates and closes a locking circuit for itself at contacts 135, and including contacts 128 of relay 102, opens the circuit of relay 103 at contacts 138, and at contacts 141 closes an additional point in the simplex control circuit. Relay 104 is made slow 25 to operate in order to allow sufficient time for relay 103 to become fully saturated. Relay 103 is a slow-releasing relay and maintains its armatures in actuated position for a short time after its circuit is opened by relay 104. Relay 103 then releases, disconnects ground from the simplex trunk and connects it through again to battery by way of contacts 134, contacts 129 and contacts 141 in parallel, contacts 147, upper winding of relay 108 30 to battery.

Returning now to the point at which relay 103 operated, ground from contacts 133 extends by way of the right hand windings of repeating coil R and trunk conductors 6 and 45 7 in parallel, left hand windings of repeating coil R1, conductor 322, contacts 320, 319 and 343, lower winding of relay 309 to battery. Relay 309 operates and at contacts 340 closes a circuit for its own upper windings and lamp L2 in parallel. Relay 309 remains operated over its upper winding after relay 103 of the connector releases and disconnects ground from the trunk. Lamp L2 lights to 50 inform the attendant that a call has come in over the trunk.

The call is answered by actuated key K1 to the right which closes a circuit for relay 307 at contacts 316, closes points in the talking circuit at contacts 315 and 317, and switches the control leg 322 of the simplex trunk from relay 309 of the trunk apparatus to the attendant's set. Relay 306 operates, opens the circuit for relay 309 and lamp L2 55 at contacts 341 and at contacts 342 prepares

a circuit for relay 307 and 308. Lamp L2 is extinguished and relay 309 deenergizes. The simple trunk now extends by way of conductor 322, contacts 320, 318, and 330, impulse contact 335 of calling device CD, and contacts 334 to ground through relay 304. Battery being now connected to the trunk at connector CC through relay 108 (relay 103 having deenergized) that relay and relay 304 of the attendant's set energize in series. A circuit is completed for relay 109 at contacts 149 and that relay energizes, prepares the impulsing circuit at contacts 153, opens the release circuit at contacts 154, and connects a direct current bridge including resistance 182 across the incoming trunk conductors at contacts 152. A circuit is also closed for relay 105 at contact 194 but the operation of this relay has no utility in this particular connection. The bridge across the incoming trunk conductors causes the operation of the ring-cut-off relay and back-bridge relays of the public exchange connector in the usual way and improves the transmission over the trunk by shunting condenser 178. The calling connector gives supervision in the usual way as when an ordinary call is answered. Returning to the attendant's set, relay 304 operates and completes a circuit for lamp L at contacts 337. Lamp L lights to indicate that the attendant's set is connected to a trunk.

The attendant may now talk with the calling subscriber, the talking circuit including repeating coils R and R1 which inductively connect the calling loop with the trunk and the trunk with the attendant's set. The local talking circuit at the attendant's position may be traced from condenser 321, right hand winding of repeating coil R1, contacts 315, 317 and 332, and the secondary winding of induction coil IC across one winding of which the receiver REC is bridged. Talking battery is applied to the primary winding of the induction coil and transmitter TR, through inductance 305, the circuit being closed by the hook switch when the attendant takes the receiver REC into use.

It is assumed that the P. B. X. party wanted may be reached at substation T1 to which a local number is assigned. The attendant now operates calling device CD in accordance with the digits of a local number and the previously traced operating circuit of relay 108 (Fig. 1) is interrupted at impulsing contacts 335. When the calling device is turned off-normal a circuit for relay 302 is closed at contacts 336. Relay 302 operates and connects direct ground to the simplex trunk at contacts 328 to improve the impulsing, and at contacts 329 opens the attendant's receiver circuit so that the dial impulses will not be audible to the attendant. Relay 108 responds to the interruptions of

its operating circuit and transmits corresponding impulses to the vertical and rotary stepping magnets of the connector. The stepping circuits, as previously mentioned, 5 are similar to those shown in the above-referred to Jacobsen patents, and will not be described in detail. It may be pointed out, however, that relays 110 and 114 which operate during the vertical and rotary stepping 10 operations, respectively, short circuit a winding of repeating coil R at contacts 155 and 167 so that the calling subscriber does not hear the impulses from the calling device. Wipers 186—188 are set on the contacts 15 of the called line in response to the dialling of two digits and the connector tests the line in the usual way. If the called line is busy relay 113 operates from ground on the test contact and locks up to ground at 20 contacts 151. Busy tone is connected to the lower talking conductor at contacts 166 and is audible both to the calling subscriber and to the attendant. The calling subscriber may hang up or may request the attendant 25 to establish a connection with another extension line. The attendant then momentarily operates key K1 to the left, opening the simplex trunk circuit, and relay 108 releases. The circuit of relay 109 is opened and that 30 relay releases and closes the circuit of the release magnet. Relay 109 also opens the direct current bridge across the incoming trunk conductors which permits the back-bridge relay of the calling connector to restore but 35 has no further effect on the call at the time. Release magnet 118 operates and the wipers of the connector restore to normal. Busy relay 113 also releases following the release of relay 109 and connector CC is placed in 40 condition for reoperation. The attendant again actuates key K1 to the right and sets up another connection exactly as in the previous instance. If the called line is idle, relay 115 of the connector operates in series 45 with the line relay of the called line and ringing current is sent over the calling line in the usual manner. The attendant will then restore key K1 to normal, thus making the telephone set available for other calls and 50 reconnecting the trunks to relay group TRG. It will be recalled that relay 307 operated over its upper winding when key K1 was operated to the right and that relay 306 was also operated. As key K1 is restored to normal, contacts 319 close before contacts 318 open and leg 322 of the simplex trunk is extended by way of contacts 342, lower winding of relay 307, relay 308 to ground. Relay 108 of the connector (Fig. 1) and relay 55 307 remain energized over this circuit and relay 308 also operates. Lamp L1 lights and remains lit until the called subscriber answers. When the called subscriber lifts the receiver the usual direct current bridge 60 across the line is closed and ring-cut-off re- lay 112 operates in the usual manner to stop the ringing and extend the called line loop to battery feed relay 107. Relay 107 operates over the called subscriber's group and at contacts 147 and 148 disconnects the upper winding of relay 108 from the simplex trunk and connects the two windings of the relay in series to the trunk. The lower winding of relay 108 has a relatively high resistance and relay 308 of trunk relay group TRG (Fig. 70 75 80 85 90 95 100 105 110 115 120 125 130 135 140 145 150 155 160 165 170 175 180 185 from a selector or switching connector level of either the public exchange or another P. B. X. will now be considered. The calling selector or switching connector having 5 been operated to the proper level automatically selects a trunk to the P. B. X., for example the trunk comprising conductors 2-4, terminating in connector CC. Ground is extended over release trunk conductor 4 to slow-release relay 103 by way of contacts 122 and 138. Relay 103 operates, closes the line conductors through to line relay 106 at contacts 131 and 132, closes a circuit for slow-to-operate relay 104 at contacts 130, and at 15 contacts 133 connects ground to the simplex trunk as in the previous connection. Relay 106 operates, closes a point in the holding circuit of relay 104, at contacts 146 disconnects release trunk conductor 4' from the relay 102 20 at contacts 196 and at contacts 195 connects a busyng ground to that conductor. The attendant is signalled and answers the call as described in the previous connection. Relays 108 and 109 operate as previously described, as does relay 105. Relay 105 by 25 means of the usual contact arrangement reverses the direction of current flow over the incoming trunk conductors for the purpose of supervising and metering the call. The 30 attendant sets up the connector and the call is completed in exactly the same manner as described for connector level calls.

Local calls within the P. B. X. are completed automatically as was previously mentioned. For example, the subscriber at substation T may call the subscriber at substation T1 by way of lineswitch LS and connector LC. On lifting the receiver at substation T a circuit is closed for line relay 40 202 of lineswitch LS and that relay operates in the usual way to complete the testing circuit of the lineswitch. The lineswitch operates in the well known manner and selects an idle trunk, for example, the trunk comprising conductors 216-218, terminating in connector LC. The calling subscriber then dials the digits of the called line number and connector LC is operated into engagement with contacts of the called line. The connector 45 tests and signals the called line in the usual manner and when the call is finished releases lineswitch LS and restores its own wipers to normal in the usual manner.

Should the subscriber at substation T desire to call the attendant, connector LC will be operated to the contacts associated with the line assigned to the attendant, for example the line terminating in lineswitch LS1. Cut-off relay 201' operates in the usual manner to disconnect relay 202' and ground from the talking conductors of the line comprising conductors 391 and 392. The connector rings out on the line in the usual manner to operate the bells B which are bridged across 55 the line conductors in series with condenser

351. The attendant answers the call by operating key K to the right, thereby extending the line conductors to the attendant's telephone set at contacts 311 and 313, disconnecting the bells and condenser from the line, and closing a circuit for relay 302 which may be traced from ground, contacts 314, and 325, upper winding of relay 302 to battery. Relay 302 operates and closes a circuit for 70 relay 301 at contacts 327. Relay 301 operates, closes a locking circuit for itself at contacts 324, opens the circuit of relay 302 at contacts 325, and closes a circuit for relay 303 at contacts 323. Relay 301 also closes a direct current bridge across the incoming line conductors at contacts 326, the bridge including the secondary winding of induction coil IC and contacts 332. The ring-cut-off relay of the connector operates over this bridge in the usual way to stop the ringing. Relay 302 75 remains energized a short time after its circuit is opened at contacts 325 due to its slow releasing characteristics and maintains the attendant's receiver circuit open at contact 329 so that ringing current will not affect the receiver. Relay 302 then deenergizes to close the receiver circuit and the attendant may converse with the calling subscriber. The operation of relay 303 substitutes the bridge 80 including the impulse contacts of the dial 90 for the first mentioned direct current bridge, but this operation has no utility in this connection. When the calling subscriber hangs up the receiver lineswitch LS and connector LC release in the usual manner. The attendant then restores key K to normal. 95

The subscriber at substation T may also call subscribers in the public exchange or in another P. B. X. by operating connector LC to a trunk level on which level the connector 100 functions as a selector. For example, by operating the connector to the tenth level the trunks, such as the one comprising conductors 224-226 may be seized. These trunks terminate in incoming selectors such as selector ISM in the public exchange through which access may be had to any of the public exchange subscriber's lines. The ninth level, for example, may be equipped with trunks 105 extending to another P. B. X., such as the trunk comprising conductors 221-223, which may terminate in either a selector or a connector in the branch exchange. The latter trunk may also terminate in a connector, such as connector CC in another private exchange, which will extend the call to an attendant for completion. 110

The attendant may also extend calls to the various P. B. X. lines or to the public exchange or to another private exchange in 115 exactly the same manner as a P. B. X. calling subscriber. To extend a call, key K is operated to the right, whereupon relays 302, 301, and 303 operate as in the previous connection, and close a loop for relay 202' of 120 130

lineswitch LS1, which may be traced from ground, contacts 209', conductor 391, contacts 318 and 326, secondary winding of induction coil IC, contacts 333, impulse contacts 335, contacts 331, and 311, conductor 392, contacts 204', winding of relay 202' to battery. Relay 202' operates, closes the usual testing circuit at contacts 210' and 211', whereupon lineswitch LS1 operates in the usual manner to select an idle trunk, such as the trunk comprising conductors 216-218, terminating in connector LC. The operation of calling device CD interrupts the calling loop at impulse contacts 335 and connector LC is operated in the same manner as previously described. Relay 302 operates when the calling device is turned off-normal, as in the previous connection and opens the receiver circuit at contacts 329. The connection is released by restoring key K to normal, thereby opening the loop circuit to lineswitch LS1 and connector LC at contacts 311 and 313. Should key K be operated while the attendant's set is connected with an incoming trunk by way of key K1, the simplex control trunk will not be opened due to the holding circuit closed at contacts 312. This permits the attendant to extend a connection over conductors 391 and 392 and lineswitch LS1 while holding up a connection from a public exchange by way of the simplex trunk. The operations under these conditions are exactly the same as those described in previous connections.

Having described the invention, what is thought new and is desired to have protected by Letters Patent will be pointed out in the appended claims.

What is claimed is:

40. 1. In a telephone system comprising a main exchange and a branch exchange, switching apparatus at the main exchange for completing connections between main exchange subscribers and branch exchange subscribers, other switching apparatus at the main exchange for completing connections between branch exchange subscribers, a branch exchange attendant's position located at a point remote from the main exchange, a main exchange trunk terminating in said first switching apparatus, and a branch of said trunk extending from said first switching apparatus to said position.
55. 2. In a telephone system comprising a main exchange and a branch exchange, switching apparatus at the main exchange for completing connections with branch exchange subscribers, a branch exchange attendant's position located at a point remote from the main exchange, a trunk extending from the main exchange to said switching apparatus, said trunk having a branch extending to said position, and means responsive to a call over said trunk for signalling the attendant over said branch.

3. In a telephone system comprising a main exchange and a branch exchange, switching apparatus in the main exchange for completing all calls within the branch exchange, a branch exchange attendant's position outside of the main exchange, a trunk extending from the main exchange to certain of said switching apparatus, said trunk having a branch extending to said position, and means responsive to a call over said trunk for rendering said certain switching apparatus directly controllable by the attendant over said branch. 70

4. In a telephone system comprising a main exchange and a branch exchange, switching apparatus in the main exchange for completing all local calls within the branch exchange, other switching apparatus in the main exchange for completing calls incoming to the branch exchange from the main exchange, a branch exchange attendant's position remote from the main exchange, subscribers' lines terminating in said first switching apparatus, a trunk extending from the main exchange to said switching apparatus, a branch of said other trunk extending to said position, means responsive to a call over said trunk for extending the call to said position via said branch, and means controlled by the attendant over said branch 90 for directly operating said other switching apparatus to further extend the call to a called line. 95

5. In a telephone system, a calling line, switching apparatus accessible to said line, a connector switch, a trunk terminating in said switch and accessible to said switching apparatus, an attendant's position, a second trunk terminating in said switch and extending to said position, means controlled by 100 the calling subscriber for directly operating said switching apparatus to extend a call to said switch via said first trunk, and means responsive to the extension of the call for rendering said switch directly controllable by the attendant over said second trunk. 105

6. In a telephone system, a calling line, switching apparatus accessible to said line, a connector switch, a trunk terminating in said switch and accessible to said switching apparatus, an attendant's position, a second trunk terminating in said switch and extending to said position, means controlled by the calling subscriber for directly operating said switching apparatus to extend a call to said switch via said first trunk, means responsive to the extension of the call for signalling the attendant over said second trunk, and means controlled by the attendant over 115 said second trunk for directly operating said switch to further extend the call. 120

7. In a private branch automatic telephone system in which the switching apparatus is located at a point remote from the subscrib- 125 130

ers' premises, an attendant's position located at the subscriber's premises, a trunk connecting the switching apparatus and said position, means for extending an incoming call 5 to said position via said trunk without directly operating said switching apparatus, and means controlled by the attendant over said trunk for directively operating the switching apparatus to further extend the 10 call.

8. In a telephone system, a directively controlled switching device, two trunks terminating in said device, a battery, and means responsive to the seizure of said device over 15 one of said trunks for successively connecting the two poles of said battery to the other of said trunks.

9. In a telephone system, a connector switch, an incoming trunk and a control 20 trunk each comprising a plurality of conductors terminating in said switch, means for extending a connection to said switch over two conductors of said incoming trunk in series, and means responsive to the extension 25 of said connection for connecting a characteristic potential to two conductors of said control trunk in parallel.

10. In a telephone system, a connector switch, an incoming trunk and a control trunk 30 each comprising a plurality of conductors terminating in said switch, means for extending a connection to said switch over two conductors of said incoming trunk in series, a battery, and means responsive to the extension 35 of said connection for successively connecting the two poles of said battery to two conductors of said control trunk in parallel.

11. In a telephone system, an automatic 40 switch, an attendant's position, two trunks terminating in said switch, means responsive to a call for seizing said switch over one of said trunks, means responsive to the seizure of the switch for signalling the attendant over the other of said trunks, means in the 45 switch responsive to the attendant's answering the call for reversing the direction of current flow over said first trunk, and means controlled by the attendant over said other 50 trunk for directively operating said switch to extend the call.

12. In a telephone system, an automatic switch, an attendant's position, two trunks terminating in said switch, means responsive 55 to a call for seizing said switch over one of said trunks, means responsive to the seizure of the switch for extending the call to said attendant via the other of said trunks, means in the switch responsive to the attendant's 60 answering the call for reversing the direction of current flow over the first of said trunks, means controlled by the attendant over the other of said trunks for directively operating said switch to further extend the 65 call to a called subscriber, and means respon-

sive to the called subscriber answering the call for increasing the resistance of said other trunk.

13. In a telephone system, an automatic switch accessible over two paths, a control 70 trunk terminating in said switch, a source of current, means in the switch responsive to its seizure over one path for connecting said current source to said trunk, and means in the switch effective when the connector is seized 75 over the other path and responsive to alternating current transmitted thereover for connecting said current source to said trunk.

14. In a telephone system, an automatic switch accessible over two paths, a control 80 trunk terminating in said switch, means in the switch responsive to its seizure over one path for rendering said switch directively operable over said trunk, and means in said switch effective when the switch is seized over 85 the other path and responsive to alternating current transmitted thereover for rendering said switch directively operable over said trunk.

15. In an automatic switch accessible over 90 two paths, a relay, means responsive to the seizure of the switch over one path for operating said relay, and means responsive to the seizure of the switch over the other path for rendering said relay operable responsive to 95 alternating current received over said other path.

16. In a telephone system, a switching device, a battery feed relay in said device, two trunks terminating in said device, means for 100 extending a call to said device over either of said trunks, means in said device responsive to the extension of a call over one of said trunks for bridging said relay across the conductors of said trunk, and means responsive 105 to the extension of a call over the other of said trunks for disabling said relay.

17. In a telephone system comprising a private branch exchange and a public exchange in which the local and incoming 110 switching apparatus of the private exchange is located at the public exchange, subscribers' stations and an attendant's switchboard located at the private exchange subscriber's premises, lines connecting the stations with 115 the local switching apparatus, and a control trunk connecting the switchboard with said incoming switching apparatus.

18. In an automatic telephone system comprising a public exchange and a private branch exchange, switching apparatus at the public exchange for completing local connections between branch exchange subscribers, other switching apparatus at the public exchange for completing calls from public exchange subscribers and branch exchange subscribers, substations and an attendant's switchboard at the branch exchange subscriber's premises, lines connecting the sub- 125 130 135

stations with said first switching apparatus, and trunk lines connecting the switchboard with said other switching apparatus.

In witness whereof, I hereunto subscribe my name this first day of July, A. D. 1929.

JOHN H. VOSS.

In witness whereof, I hereunto subscribe my name this first day of July, A. D. 1929.

THOMAS F. CROCKER.
